Primary Examiner — Randall Gholson

(72) Inventor: **Ejaz Dean**, Honolulu, HI (US)

(57) **CLAIM**
The ornamental design for a dual hollow square wrench handle, as shown and described.

(***) Term: **14 Years**

DESCRIPTION

(21) Appl. No.: **29/487,080**

FIG. 1 is a top perspective view of my new design for a dual hollow square wrench handle;
FIG. 2 is a bottom perspective view thereof;
FIG. 3 is a right side view thereof;
FIG. 4 is a left side view thereof;
FIG. 5 is a front view thereof;
FIG. 6 is a back view thereof;
FIG. 7 is a top view thereof; and
FIG. 8 is a bottom view thereof.

(22) Filed: **Apr. 4, 2014**

FIG. 9 is an alternate embodiment top perspective view of my new design for a dual hollow square wrench handle;

(51) **LOC (10) Cl. 08-05**

FIG. 10 is a right side view thereof;

(52) **U.S. Cl.**

FIG. 11 is left side view thereof;

USPC **D8/27; D8/28**

FIG. 12 is a top view thereof; and,

(58) **Field of Classification Search**

FIG. 13 is a bottom view thereof.

USPC D8/17, 21-29, 354, 107; 81/60, 177.1,
81/177.85, 121.1, 124.3, 165-170, 110.1,
81/176.2, 124.6, 176.1, 176.15, 177.2,
81/186; 16/110.1; D15/144.1, 143;
219/75, 227, 229, 121.16, 121.18

The broken lines depict portions of the dual hollow square wrench handle that form no part of the claimed design.

See application file for complete search history.
